PARKING METER ADVERTISING DEVICE

Charles L. Sandahl, Jr., and James O. Hopkins,
Austin, Tex., assignors, by mesne assignments,
to Parking Meter Advertising Company of
Memphis and Nashville, Tennessee, a corpora-
tion of Tennessee

Application May 23, 1949, Serial No. 94,794

4 Claims. (Cl. 40—145)

The present invention relates to improvements in a parking meter advertising device and has for an object the provision of a device of this kind which may be removably attached to the post of the conventional parking meter at any desired height.

Another object of the present invention is to provide an improved structure in which the advertising bearing sign plates may be quickly and easily detached from their supporting brackets so that other sign plates bearing different advertising matter may be substituted.

A further object of the present invention is to provide an improved advertising sign of this character in which two separate securing means are provided for holding the clamping member on the post of the parking meter, one of said securing means comprising one of the sign plate supporting brackets and the sign plate.

A still further object of the present invention is to provide an improved advertising device in which one of the securing means for holding the clamping member on the post is partially concealed from view and is not readily accessible for loosening in order to make more difficult tampering with or removal by an unauthorized person.

In one of its broadest aspects the present invention contemplates the provision of an improved parking meter advertising device comprising a pair of pivotally connected semi-circular arms for clamping around the parking meter post, lugs carried by said arms, securing means mounted on said lugs for holding said arms in engagement with the post, a plurality of sign plate supporting brackets mounted on said arms and sign plates attached to said brackets.

With the foregoing and other objects in view, the invention will be hereinafter more fully described and more particularly pointed out in the appended claims.

In the drawings, in which the same parts are denoted by the same reference numerals throughout the several views:

Figure 1 is a perspective view of a parking meter having mounted thereon the improved device constructed in accordance with the present invention;

Figure 2 is a top plan view of the improved device illustrated as attached to a parking meter post which is shown in transverse section;

Figure 3 is a sectional view taken on the line 3—3 of Figure 2 and looking in the direction of the arrows;

Figure 4 is a sectional view taken on the line 4—4 of Figure 2 and looking in the direction of the arrows; and

Figure 5 is a top plan view of the improved device in inoperative position and with the sign plates removed.

Referring more particularly to the drawings, a clamping member is generally indicated at A and comprises a pair of substantially semi-circular arms 10 and 11 provided with bearings which may be in the form of apertured ears 12 and 13, respectively. The ear 12 extends laterally from the upper portion of the arm 10 and its lower face has overlapping engagement with the upper face of the ear 13 of the arm 11 which extends laterally from the lower portion of the arm 11. A pivot which may be in the form of a pin 14 extends through the aligned apertures of the ears 12 and 13 when they are in overlapped relation. One end of the pin 14 has an enlarged head 15 and its opposite end portion has an opening for receiving a cotter pin 16 or the like to prevent the escape of the pivot pin 14 from the apertured ears.

25 The free ends of the arms 10 and 11 are bent outwardly therefrom at an angle of the order of ninety degrees to form lugs 17 and 18, respectively, which are provided with openings 19 and 20, respectively. A fastening element which 30 may be in the form of a screw threaded bolt 21 extends through the aligned openings 19 and 20 of the lugs 17 and 18 when the arms 10 and 11 are brought into clamping engagement with a post 22 of a parking meter 23. The bolt 21 is held in its operative position by a nut 24.

35 A sign plate supporting bracket comprises sections 25 and 26 which are mounted on the lugs 17 and 18, respectively, and are disposed at an angle of the order of ninety degrees thereto.

40 The sections 25 and 26 extend in opposite directions to one another and overlie the lugs 17 and 18 and bolt 21 and nut 24. The bracket sections 25 and 26 may be formed separately from the lugs 17 and 18, respectively, or may be cast 45 integrally therewith. Each of the sections 25 and 26 is substantially rectangular in shape and is provided with a screw threaded hole 27.

45 A sign plate 28 having holes 29 which register with the holes 27 in the sections 25 and 26 is 50 detachably mounted on the sections by screws 30 which are received by the aligned holes in the sections and plate.

55 Adjacent their pivotally connected ends, the arms 10 and 11 have webs 31 and 32, respectively, 55 which may be formed separately from the arms

or may be cast integrally therewith. The webs 31 and 32 have mounted thereon brackets 33 and 34, respectively, which are provided with screw threaded holes 35. Sign plates 36 and 37 are detachably mounted on the brackets 33 and 34, respectively, by screws 38 or the like which extend through suitable holes in the sign plates 36 and 37 and the brackets 33 and 34, respectively. The sign plates 28, 36 and 37 may be made of metal, plastic or rubber and may be of any desired configuration, but in the present illustration are substantially square and when mounted upon the post 22 of the parking meter form a substantially equilateral triangle. The sign plates are adapted to have inscribed thereon advertising matter, information or other desirable matter.

In the use of the device, assuming that the sign plates have been removed from the brackets and that the nut 24 and the bolt 21 have been removed from the lugs 17 and 18, the arms 10 and 11 may be moved apart on their pivot 14 until the space between the free ends of the arms is sufficiently large to permit the clamping member A to encircle the post 22 of the parking meter 23. The clamping member A may then be securely attached to the post 22 by means of the bolt 21 and the nut 24.

During the opening and closing movements of arms 10 and 11 the contacting surfaces of the ears 12 and 13 will act as bearing surfaces. This arrangement will properly guide the arms in their pivotal movements so as to maintain the arms and the openings 19 and 20 of the lugs 17 and 18 in proper alignment to facilitate the insertion of the bolt 21 therein. The clamping member A may be positioned at any suitable height on the post 22 and the nut 24 may then be tightened to maintain the device in the selected position. The sign plates may then be mounted upon their respective brackets.

It will be noted that when the sign plate 23 is secured to the bracket sections 25 and 26, it will provide an additional securing means for holding the arms 10 and 11 in clamping relation to the post 22. The bracket sections 25 and 26 and the sign plate 23 will also overlie and partially conceal the bolt 21 and the nut 24. This arrangement will, to some extent, protect these parts against the elements and will also serve to make it more difficult for an unauthorized person to tamper with or remove the device from the parking meter.

The sign plates are so mounted on their brackets that they may be quickly and easily attached thereto and removed therefrom. This will provide a means of substituting new sign plates.

It is obvious that various changes and modifications may be made in the details of construction and design of the above specifically described embodiment of this invention without departing from the spirit thereof, such changes and modifications being restricted only by the scope of the following claims.

What we claim is:

1. An improved parking meter advertising device comprising a clamping member comprising a pair of pivotally connected semicircular arms for embracing the post of the parking meter, a lug on the free end portion of each arm and extending outwardly therefrom at an angle of the order of ninety degrees, contracting means mounted on said lugs for clamping the arms around the post and into tight frictional engagement therewith to prevent rotative movement of

the clamping member with respect to the post, a sign plate supporting bracket supported by at least one of said lugs and being disposed at an angle of the order of ninety degrees thereto, said bracket being provided with an opening, an advertising bearing sign plate adapted to be secured to said bracket and having an opening therein in alignment with the opening in said bracket, and a fastening element extending through said aligned openings for attaching said plate to said bracket.

2. An improved parking meter advertising device comprising a clamping member comprising a pair of pivotally connected semicircular arms for embracing the post of the parking meter, a lug mounted on the free end portion of each arm, contracting means mounted on said lugs for clamping the arms around the post, a sign plate supporting bracket connected to each of said lugs, each of said brackets being provided with an opening, an advertising bearing sign plate adapted to be secured to said brackets and having openings therein in alignment with the openings in said brackets, and fastening elements extending through said aligned openings for attaching said plate to said brackets, said lugs extending outwardly from said arms at an angle of the order of ninety degrees and said brackets extending at an angle of the order of ninety degrees to said lugs for overlying said contracting means.

3. For use with a parking meter having a post, an improved advertising device comprising a pair of pivotally connected semicircular arms adapted to be clamped around said post, contracting means mounted on the free end portions of said arms adapted to clamp the arms around said post and into tight frictional engagement therewith to prevent rotative movement of the clamping member with respect to the post, the combined inside circumference of said arms being less than the outside circumference of the post, whereby when said arms are clamped around the post the free end portions of the arms are spaced apart, a sign plate supporting bracket mounted on the free end portion of each arm and having an opening therein, a sign plate adapted to be detachably mounted on said brackets so as to bridge the space between the free end portions of said arms and having openings therein in alignment with the openings in said brackets, fastening elements extending through said aligned openings for attaching said plate to said brackets, and a sign plate supporting bracket mounted on each arm intermediate the ends thereof and adapted to detachably support a sign plate.

4. An improved parking meter device comprising, a pair of pivotally connected substantially semicircularly shaped arms for embracing the post of a parking meter, said arms each having a projecting portion at the free end thereof, means cooperating with said projecting portions to clamp said arms around the parking meter post and into tight frictional engagement therewith to prevent the device from rotating, a sign plate supporting member carried by at least one of said pivotally connected arms at the free end projecting portion thereof, a second sign plate supporting member carried by one of said pivotally connected arms intermediate the pivot point and free end portion thereof, a third sign plate supporting member carried by the other of said pivotally connected arms intermediate the pivot point and the free end portion thereof, each of

said sign plate supporting members being adapted to carry an advertising sign plate, said sign plate supporting members being positioned with reference to each other to provide a triangular configuration when sign plates are secured thereto. 5
